J.B. Robinson,

Horse Power,

Patented Oct. 14, 1816.

264X
14 May 1820
(To all whom these presents shall come, Greetings.

I BEAR ASW. that the annexed is a true Copy of the Specification making part
of the Patent granted to Joseph Best Relating to his Improvement in the Inclined
Horse wheel dated the 14th of October 1816.

In Testimony whereof, I, Wm D. Adams
Secretary of State of the United States, have caused to be
scribed my name and caused the Seal of the Depart-
ment of State to be affixed.

Done at the City of Washington this second day
of May A.D. 1820

W. D. Adams

(Description of the inclined Horse Wheel (mentioned in the above Specification.)

The arms of the inclined Horse wheel pass through a shaft at right angles and are planted on in such a manner as to sustain the weight of one or more horses. The shaft is inclined from a perpendicular about ten degrees which of course inclines one side of the wheel ten degrees above and depresses the other side ten degrees below the horizon, a horse therefore placed behind the extremes by his weight carries round the wheel and must of necessity continually walk in order to retain his position. The arms of the wheel may be braced from the shaft either above or below the wheel or both, a cog wheel may be affixed either to the upper side or under side of the arms, or to other arms passing through the shaft either above the Horse wheel or below it, levers may be affixed either to the upper or under sides of the edge to make machinery more powerful, so as to proportion the power & velocity in any manner found most useful. The diameter of the wheel and length of the shaft may be also increased or diminished to suit the wants of boats, the extent of boats, manufacturers &c which may be put in motion by the wheel. On the shaft of the Wallace, a balance wheel should be affixed especially for steam Mills when some and may be proportioned to the extent of machinery put in motion (incor-
(11 Sept 5 1816))
